UNITED STATES PATENT OFFICE.

JOSEPH F. CARROLL, OF CONCORD, NEBRASKA.

CRATE.

1,118,738.

Specification of Letters Patent.

Patented Nov. 24, 1914.

Application filed February 24, 1913. Serial No. 750,221.

To all whom it may concern:

Be it known that I, JOSEPH F. CARROLL, a citizen of the United States, and a resident of Concord, in the county of Dixon and State of Nebraska, have invented a new and Improved Crate, of which the following is a full, clear, and exact description.

My invention relates to an improvement in crates for shipping farm produce and the like; and the object thereof is to produce a crate the sides and ends of which can be made out of a single blank of metal, such as sheet steel, so stamped as to provide the necessary openings for ventilation, and at the same time having sufficient strength and rigidity to protect the contents.

Reference is to be had to the accompanying drawings forming a part of this specification, in which the same characters of reference indicate the same parts in all the views.

Figure 1 is a perspective view of my crate with the top removed and the bottom in place; Fig. 2 is a vertical transverse sectional view of the crate; Fig. 3 is a view of the blank comprising the sides and ends folded together; Fig. 4 is a plan of the top; Fig. 5 is a plan of the bottom; Fig. 6 is a plan of the blank comprising the sides and ends; Fig. 7 is a perspective view showing one corner of the crate, illustrating more fully the construction thereof; Fig. 8 is a perspective view of a modification.

My crate comprises a single sheet of metal 1, such as sheet steel, so shaped and bent after stamping as to form ends 2 and sides 3. These sides and ends receive a top 4 and support a bottom 5, so as to house the contents of the crate completely. The blank 40 which is shaped to form the sides and ends is shown in detail in Fig. 6, and in one longitudinal edge of this blank I form recesses 6 adjacent the bottom of end-forming portions 2, and these recesses 6 are connected by edges 7 within the portions 2 and by edges 8 within the portions forming the sides 3. The side-forming portions 3 are of somewhat greater width than the end-forming portions 2, so that the edges 7 and 8 are not 50 in alinement, and it will be seen that the edges 8 are of the same length as the length of the side-forming portions 3, while the edges 7 are of somewhat less length than the end-forming portions 2, owing to the formation of the recesses 6 above mentioned. Along the edge of the plate 1, opposite the

edge in which the recesses 6 are formed, I make cuts 9. These cuts will be at the corners of the crate when the same is set up, and each of these cuts will be in line with an edge of one of the recesses 6. The purpose of the cuts 9 will be set forth later.

At the end of one side-forming portion 3 is a reduced section 10 separated from the body of this portion by means of shoulders 63 11, and this portion 10 is bent so as to receive the outer edge of one end-forming portion 2, and be fastened thereto when the crate is made up. This section 10 is bent over at right-angles to the adjacent side-forming portion, and the edge 12 of the proper end-forming portion 2 may be secured to the section 10 by riveting, soldering, or any other convenient way.

The sheet of metal 1 is provided with a 73 number of cuts 13 in the end-forming portions 2, and a number of similar cuts for the side-forming portions 3, and at the ends of each of these cuts 13 are short cross cuts 14. The lines along which the side-forming portions and end-forming portions are bent are indicated at 15, these lines extending between one side of the recesses 6 and the cuts 9 which extend inward from the edge of the plate 1, and before the plate 1 is bent so as 80 to bring the side-forming portions and end-forming portions into proper relative position, the portions of the plate 1 along the edges of the cuts 14 are rolled over, as shown at 16, leaving open spaces 17 to admit air 90 into the crate. The portions between the spaces 17 in the ends and sides form slats, and the rolled-over edges of these slats help to strengthen the crate. In the form shown in Figs. 1 to 7, which is the preferred construction, the members 16 run horizontally. In this form also and arranged along the length of the portions forming the slats of the crate I form ribs 18 parallel with the members 16. These ribs are located midway 100 between the rolled-over edges 16 of each slat and they are of greater length than the cuts 13, so that each of the ribs 18 will extend past the ends of the open spaces 17 to the corner line of the crate. The location 105 of the ends of the ribs 18 in proximity to each other marks the lines along which the plate 1 is bent, and this line is indicated by the broken lines 15 on Fig. 6. These ribs 18 not only strengthen the construction of 110 the box, but prevent the plate 1 from being bent in the wrong place, and in order to

make sure that the plate 1 will be properly bent when the crate is to be assembled, I may score the plate 1 along the lines 15, if desired.

5 The edges 7 are rolled over between the recesses 6 to form ribs 19 at the bottoms of the ends of the box, and the edges are also rolled over to form ribs 20 at the bottoms of the sides. The ribs 19 will be of slightly 10 less length than the length of the ends and will normally be slightly above the ribs 20 when the crate is finished, as shown in Fig. 2. The ribs 19 are given such relative dimensions and positions to avoid having them 15 interfere with the ribs 20. It will be seen that both the ribs 19 and 20 are inturned and the bottom 5 rests upon the end ribs 19. This bottom is provided with longitudinal 20 corrugations shown at 21 to prevent the same from being readily bent in a transverse direction.

The top of the crate 1 is rolled over between the cuts 9 to form ribs 22, and the open top of the crate is closed by the cover 25 4. This cover is provided with longitudinal ribs or corrugations 23, and its edges are stamped so as to form grooves or concave ribs 24 into which the round ribs 22 snugly fit. The top can be fastened in place by any 30 convenient means.

From the above description it will be seen that I have produced a crate of light, strong and cheap construction. The blank from which the ends and sides are made can 35 be stamped out of a single sheet of metal, and while I have shown this blank in the form of a plate 1 in Fig. 6 with only the recesses 6, cuts 9 and cuts 13, it is obvious that I may also stamp the ribs 18 in the 40 plate by the use of a properly designed die in the same operation that forms the plate as Fig. 6 illustrates the same. The lid or cover 4 and bottom 5 are of course stamped separate, and when the plate 1 is bent so 45 that when the ends and sides take the position shown in Fig. 3, the cover 4 and bottom 5 can be laid on top of the sides and ends and make up a very compact bundle for 50 shipment. In fact, the crate blank and its top and bottom occupy very little space when not assembled and is of very little weight; it is easy to set up for use; does not splinter from rough handling when in transportation; is very easy to move about, and 55 is cooler and drier for shipping or storage because the metal parts of the crate do not absorb moisture.

Of course the crate will be painted a suitable color, and any marks desired may be 60 added to the exterior of the same.

In the modification shown in Fig. 8, the crate, which also is produced from a single sheet, is formed with vertical openings 17^a, the material at the vertical edges of the 65 openings being turned to produce vertical

ribs 16^a, and between and paralleling the openings, and extending beyond the ribs 16^a, are ribs 18^a formed by pressing the material outward. The first described construction, with its horizontal ribs, is preferable. The 70 top edges 22^a of the sides 3^a and ends 2^a, in the form shown in Fig. 8, are turned over as in the other form, as well as the corresponding bottom edges 19^a, 20^a. To join the meeting edges of the plate from which the 75 crate is formed, I may produce projecting lugs 10^a on one end portion 2^a to overlap the adjacent sides 3^a, the connection being completed by rivets 10^b.

Having thus described my invention, I 80 claim as new and desire to secure by Letters Patent:

1. A sheet metal crate comprising sides and ends, the ends having shoulders adjacent the corners of the crate to form projecting 85 lower edges, said edges above the lower edges of the sides and being rolled over to form internal ribs, and a bottom extending from one end to the other of the crate supported by said ribs, the lower edges of the 90 sides being rolled over to form rests below the ends and bottom.

2. A crate comprising sides and ends made of a single plate of metal, said plate having cuts extending transversely into the same 95 from one edge, and recesses extending into the same from the opposite edge, said cuts and said recesses marking the lines along which the plate is to be bent to form the corners of the crate, the end-forming portions being of less width than the side-forming portions and having their lower edges above the lower edges of the sides, the said edges being rolled over, the recesses being located so as to lie within the outlines of the 100 end-forming portions, and the plate having longitudinal cuts in the end-forming portions and side-forming portions with transverse cuts at the ends of the said longitudinal cuts, and means carried by the plate to 105 secure the ends of the same together after the same has been bent.

3. A crate comprising sides and ends made of a single plate of metal, said plate having cuts extending transversely into the same 115 from one edge, and recesses extending into the same from the opposite edge, the outer side walls of the recesses being straight with the cuts at the opposite edge and defining the perpendicular side edges of the lower portions of the sides of the crate, said cuts and said recesses marking the lines along which the plate is to be bent to form the corners of the crate, the end-forming portions being of less width than the side-forming portions and having their lower edges above the lower edges of the sides, the said edges being rolled over, the recesses being located so as to lie within the outlines of the end-forming portions, and the 120 125 130

plate having longitudinal cuts in the end-forming portions and side-forming portions with transverse cuts at the ends of the said longitudinal cuts, and means carried by the 5 plate to secure the ends of the same together after the same has been bent.

4. The herein described sheet metal blank for forming crate bodies, said blank having transverse bending lines defined thereon between end panels and side panels, transverse 10 cuts in one longitudinal edge of the blank in line with the said transverse bending lines, and recesses in the opposite longitudinal edge of the blank at the sides of the end

panels, said end panels terminating at the 15 recessed edge short of the edges of the side panels and the outer walls of said recesses being straight with the transverse bending lines and defining the perpendicular side edges of the lower portions of the side 20 panels.

In testimony whereof I have signed my name to this specification in the presence of two subscribing witnesses.

JOSEPH F. CARROLL.
